UNITED STATES PATENT OFFICE.

WILLIAM E. SQUIER, OF BURKBURNETT, TEXAS.

DIRECTION SIGNAL FOR AUTOMOBILES.

Application filed March 6, 1922. Serial No. 541,388.

To all whom it may concern:

Be it known that I, WILLIAM E. SQUIER, a citizen of the United States, residing at Burkburnett, in the county of Wichita and State of Texas, have invented certain new and useful Improvements in Direction Signals for Automobiles; and I do declare the following to be a full, clear, and exact description of the invention, such as will 10 enable others skilled in the art to which it appertains to make and use the same.

This invention relates to an improved direction signal for automobiles and similar vehicles and one object of the invention is 15 to provide a direction signal which may be mounted at the front or at the rear of the automobile and may be operated to display a signal and at the same time illuminate it so that the signal may be readily seen.

Another object of the invention is to provide improved means for controlling turning of the indicating element from one position to another and to so construct this controlling mechanism that when a switch is 20 closed to bring selected contact elements into engagement, a circuit may be completed until the indicator has turned to the desired position, the circuit being then broken to permit a latching element to move into an operative position and hold the indicating element in the desired position.

Another object of the invention is to construct this device that contact elements carried by a movable element of the switch 35 may be connected with contact elements engaging a sleeve extension of a gear carried by the stem rotatably mounting the indicator element, this sleeve being provided with insulating blocks causing bridging of a closed circuit when the indicator element 40 has been turned to the desired position.

Another object of the invention is to so construct this signal that it may be provided with a single indicator element 45 when used at the rear of an automobile or with indicator elements extending in diverging relation so that the indicators may be seen from the front or at one side when the signal is used at the front of the car.

Another object of the invention is to provide a direction signal which will be relatively simple in construction and very efficient in operation.

This invention is illustrated in the accompanying drawings, wherein:

Figure 1 is a top plan view of the forward end portion of an automobile showing a signal of the improved type connected with the filling neck of the radiator.

Figure 2 is an enlarged top plan view showing the motor housing with the top removed and the radiating arms extending therefrom.

Figure 3 is a vertical sectional view taken along the line 3—3 of Fig. 2.

Figure 4 is a similar view with the arm extension of the housing shown in full length and showing a wiring diagram and switch associated therewith and shown applied to a rear signal having a single arm 70 extension from the housing.

Figure 5 is a sectional view taken along the line 5—5 of Fig. 4.

This improved direction signal is provided with a housing 1 which may be provided with a single indicator containing arm or chamber 2 as shown in Figs. 4 and 5 or may be provided with a pair of these arms or chambers 2 which will extend in diverging relation to each other as shown in Figs. 80 1 and 2 so that the signal may be readily seen by persons in front of the automobile or at one side thereof. A rear signal will be mounted by means of a suitable bracket as indicated by dotted lines in Fig. 4. The 85 front signal will be preferably provided with a clamp extension 3 which extends from the motor housing 1 between and preferably below the arms 2 so that this clamp may be secured about the filling neck of the radiator. Within each of the side arms there has been provided an indicator element in the form of a box or casing 4 having its side walls provided with cutouts covered by 90 transparent sheets 5 upon which will be 95 printed statements indicating the movement the automobile is about to take. This box has a head at one end provided with an opening which receives the socket 6 to carry the bulb 7, this socket 6 being carried by the 100 closure 8 at the end of the stationary arm 2. At the opposite end of the box, there has been provided a hollow pivot stem extension 9 which extends through a bearing 10. It will thus be seen that the indicator will be 105 rotatably mounted in the arms 2. It will be

further noted that since the pivot stem 9 is hollow, a power wire 11 which will be connected with the lighting system of the automobile may be passed into the motor housing 1 and through the hollow pivot stem 9 and connected with the socket 6, this socket 6 being grounded so that the circuit will be completed through the lamp. In order to impart rotary movement to the indicator, there has been provided an electrically operated motor which will have a conventional construction and is indicated in general by the numeral 12. This motor is secured in the motor housing by means of a fastener 13 which passes through the head 14 at the lower end of the housing and is provided with the usual shaft 16 upon which will be mounted a beveled gear 17 which meshes with a beveled gear 18 carried by the pivot stem 9 and provided with a side extension or thickened portion 19. In the form of signal used at the front of the automobile and provided with the two arms 2, the beveled gear engaged by the gear 17 may be provided with a further extension forming a beveled gear 20 or this gear 20 may be formed as a separate element and secured upon the pivot stem 9. This beveled gear 20 meshes with a similar gear 21 carried by the pivot stem 30 of the second indicator so that when the motor is in motion, both indicators will be rotated a like amount. A sleeve 22 which may or may not be formed integral with the gear 18 is fast upon the stem extension 9 and will be formed of metal so that current may pass through the sleeve to the stem extension 9 and through this stem to the motor housing. Blocks 23 which are formed of insulating material are embedded in the sleeve 22 at points about its circumference and are so located that when one of the blocks is engaged by its co-operating contact arm 24, the remaining contact arm 24 will still be in engagement with the sleeve. These contact arms 24 are carried by a strip 25 formed of insulating material which is carried by a bracket 26 secured against the side of the motor housing. This bracket 26 in addition to carrying the insulating strip 25 also carries an electro-magnet 27 and a standard 28 upon which will be pivotally mounted a latch lever 29 which extends for engagement with the side extension 19 of the gear 18 and will be yieldably held in position for engagement by the abutment pin 30 of this extension 19 by means of a spring 31. The handle end portion 29' of this latch lever extends over the electro-magnet so that when the electro-magnet is energized, the latch lever will be swung upwardly out of position for engagement by the abutment pins 30. A spring strip 32 is secured against the wall of the motor housing and has its free end portion resting upon the peripheral edge of the side extension 19 so that the

pins may readily pass this spring strip when the gear 18 is rotating in one direction. The spring strip however serves to prevent reverse movement of the gear and pivot stem and therefore after the signal has been moved to the desired position, it cannot move in a reverse direction. From an inspection of Fig. 5, it will be readily seen that with the latch lever in the operative position, a pin 30 will be positioned between the latch lever and the free end of the spring strip and thus the indicator will be securely held against movement out of the desired position. This motor 12 is connected with the electro-magnet by the usual wires 33 and is grounded upon the head 14 which closes the lower end of the motor housing by means of a grounding wire 34. The wire 35 which extends from the electro-magnet leads to the battery or other source of electric energy 36. It will thus be seen that when current is passing through one of the wires 37 which leads from the contact arm 24, this current must pass through the sleeve 22 and pivot stem 9 to the motor housing and then pass through the wire 34 to the motor to energize the motor and through the wire 33 to energize the electro-magnet and back through the wire 35 to the battery 36.

The switch device which is used in connection with this direction signal is provided with a housing 38 which will be located at a point where it can be conveniently reached by the operator of the automobile. A strip 39 is pivotally mounted in this housing 38 upon a fulcrum 40 and is provided with lug extensions 41 which carry contacts 42 for engagement by contacts 43 carried by strips 44 and 45. These strips 44 and 45 are placed in the housing 38 above the end portions 39 and held in spaced relation to the strips 39 by means of links 46. Buttons 47 are provided so that when desired the strip 44 or the strip 45 can be rocked against the fulcrum 48 or 49 and a selected contact 42 brought into engagement with a selected contact 41 and thus complete a circuit so that the current can pass through one of the wires 49 to the battery.

When this signal is in use, it will be mounted upon the automobile and in the preferred form a signal will be placed at the rear of the automobile and another mounted at the front thereof. The wires 35 and 37 will of course be provided with branches so that the two signals may be simultaneously operated from a single switch, which as previously stated will be located at a point where it can be conveniently reached by the operator of the car. When it is desired to indicate that a turn is to be made or it is desired to convey other suitable information to a pedestrian or the driver of another car, the appropriate button 47 will be pressed downwardly and this will swing one end of the

strip 44 or 45 downwardly and bring the desired contact 43 into engagement with the co-operating contact 42. This will complete a circuit which will cause the motor to be energized and the electro-magnet to be energized. The electro-magnet will draw the handle end portion 29' of the latch lever 29 downwardly and thus move the latch lever upwardly out of the way so that the gear 18 may rotate and thus turn the indicator 4 within the arm or casing 2. This rotation will continue as long as the contact arm 24 which is connected with the depressed contact 43 is in engagement with the metal sleeve 22 but as soon as the contact arm 24 engages the co-operating insulating block 23, the circuit will of course be broken by this insulating block and the flow of current through the motor and electro-magnet prevented. The operation of the motor will cease and the latch lever will be released so that the spring 31 can draw it downwardly into engagement with the extension 19 of the gear 18. The elements will then again assume the normal position with a pin positioned between the free end of the strip 32 and the free end portion of the latch lever 29. The indicator will thus be secured in the desired position and since this indicator is illuminated by the bulb 7, the signal will convey the desired information. Of course, if the signal is already set in the desired position, downward pressure upon a button will not cause further operation as the contact arm 24 which would otherwise be in engagement with the sleeve 22 will be in engagement with a block 23 and the circuit will be interrupted. There has thus been provided a signal which will operate very efficiently and can be used at the front of an automobile and at the rear thereof.

I claim:

1. In a signal structure, a support, an indicator having a mounting stem rotatably carried by said support, an electrically operated drive for said indicator carried by said support, latch means for controlling rotation of the indicator and including a latch lever, a releasing magnet serving to move the lever to an inoperative position, a gear carried by said stem and turning with the indicator and having engagement with a gear carried by said drive, abutment pins extending radially from said gear for engaging the latch lever when the latch lever is in an operative position to hold the gear against rotation in one direction, a spring strip engaging the gear in spaced relation to the latch lever whereby an abutment pin may be confined between the latch lever and spring strip to hold the gear and indicator against rotary movement in either direction, an energizing circuit for said drive and latch release, and means for breaking the circuit and permitting movement of the latch to an operative position.
2. In a signal structure, a rotatably mounted indicator, an electrically operated drive for said indicator, means for transmitting movement from said drive to said indicator including an element carried by and turning with said indicator, abutment pins extending from said element, a latch movably mounted and yieldably held in an operative position for engaging a pin and preventing rotation in one direction, electrically operated means for moving said latch to an inoperative position, a spring strip extending in spaced relation to said latch whereby a pin may be confined between the latch and spring strip and the indicator held against rotation in either direction, an energizing circuit for said drive and latch releasing means, and means moving with the indicator for interrupting the flow of current and permitting return of the latch to an operative pin engaging position after a pin has passed said spring strip.
3. In a direction signal, a support, a rotatable indicator including a pivot stem rotatably carried by said support, a gear and sleeve carried by said stem and turning with the stem, the gear being thickened to provide a side extension, abutments extending radially from the side extension of the gear, a resilient strip having a free end portion extending circumferentially of the gear and permitting rotation thereof in one direction and through engagement with the abutments preventing reverse rotation, a pivotally mounted latch yieldably held in engagement with side extension of said gear for engagement by the abutments to hold an abutment between the latch and resilient strip and hold the gear against rotation in the first direction, an electro-magnet for moving the latch to a releasing position, an electrically operated motor for imparting rotary movement to said gear, an energizing circuit including a movable contact, and means moving with said sleeve for moving said contact to break the circuit after the indicator has moved to a desired position.

In testimony whereof I have hereunto set my hand.

WILLIAM E. SQUIER.
